(57) **CLAIM**

The ornamental design for a wireless communication device, as shown and described.

DESCRIPTION

FIG. 1 is a perspective view of a wireless communication device according to my new design taken from the front, right side and bottom thereof;

FIG. 2 is a perspective view taken from the rear, left side and top thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in all figures illustrate portions of the wireless communication device that form no part of the claimed design.

1 Claim, 6 Drawing Sheets
